BALL WINDING MACHINE

Paul Rekettye, Akron, Ohio, assignor to The Sun Rubber Company, Barberton, Ohio, a corporation of Ohio

Application July 3, 1951, Serial No. 235,042

9 Claims. (Cl. 242—3)

1

The present invention relates to the manufacture of play balls or other spherical objects in which a layer or layers of cord or filament are wound about the center or core of the ball. Specifically, it is intended for wrapping layers of cord about a kapok center such as employed in the manufacture of baseballs of the hard or soft variety. These balls are generally made of a compressed center of kapok or the like, over which are applied two cord layers, the first being a winding of a dual heavy cord and the second a winding of a single finer cord. The cord layers are wound under considerable tension and the winding must be evenly applied so that the finished ball is a true sphere. It is also necessary that the exact amount of cord be applied in each wrapping so that the finished balls are all of uniform size. The machine shown and described herein will perform the winding operations so that every requirement for a perfect ball will be met. After the ball is wound, the cover is placed thereon.

The machine is designed so that after the correct amount of winding has been applied to the ball, the rotation of the ball and the winding will be stopped. The machine is adapted to operate upon a plurality of balls at the same time, and the operation is conducted so that the stoppage in winding of the several balls will occur in a regular order so that the completion of the winding operation on one ball will not affect the others and the operator may take out one ball at a time and replace it with a new center while the winding of the other balls continues.

In the proposed form of the invention shown and described herein, the machine is made in two parts, each of which will be given to winding one type of cord layer, but this is not an essential part of the invention as the principles thereof may be applied to a single ball winding operation. It will also be understood that the machine is not restricted to the winding of the particular type of ball described, but may be applied to other similar operations.

The invention is shown in its preferred operative form, but changes, modifications and improvements may be made therein without in any way departing from the principles of the invention.

In the drawings, in which the preferred form of the invention is shown:

Fig. 1 is a plan view of the perfected form of the machine which is of the dual type for both types of cord windings.

Fig. 2 is an end view of the machine, the loca-

tion of the view being shown by the section line 2—2 on Fig. 1.

Fig. 3 is a front elevation of one side of the machine, the location of the view being indicated by the section line 3—3 of Fig. 1.

Fig. 4 is a vertical section through the traversing mechanism, this view being taken on the line 4—4 of Fig. 1.

Fig. 5 is a vertical section through one of the ball cradles, this view being taken on the line 5—5 of Fig. 1.

Fig. 6 is a section on the line 6—6 of Fig. 5 showing one of the cord tensioning devices.

Fig. 7 is a developed view of the cam track which governs the movement of the traversing mechanism which in turn governs the shifting of the plane of rotation of the ball in the cradle.

Fig. 8 is a section along the traversing shaft on the line 8—8 of Fig. 1.

Fig. 9 is a view of a completed ball, the several outer layers of which are stepped down.

Referring to Fig. 9, a typical ball B, such as the machine is adapted to wind, comprises the compressed kapok center shown at 1. The first wrapping of heavier dual cord is shown at 2; the second wrapping of finer cord at 3, and the cover at 4.

In describing the machine, the right hand side is chosen for detailed description, it being understood that both sides of the machine are alike. It will be understood that while the right hand side of the machine is shown for the dual cord, either side may be used for single or dual wrapping. In Fig. 1, the extreme right hand ball holding cradle is shown in its outer or retracted condition, as it would appear when the winding operation on that ball is completed. All of the cradles will, under usual operating conditions, move to this outer position in series, as the individual winding operations are completed.

The machine comprises a bed plate 10 which extends across the whole machine and is supported at its corners by uprights 11. Angle iron beams 12 are attached to the upper ends of the uprights 11 and midway of the uprights is located a horizontal platform 14. Across the front of the machine is a cover plate 13 which is removed in some of the views. Suspended by rods 15 from the platform 14 on either side of the machine is a plate 16 on which is mounted the motor 18 which drives the traversing shaft and cam referred to above, which rotate the ball cores for the winding operations in the different planes. Operation of the motor is controlled through a

switch 19 located at a convenient point on the front of the machine.

At either side of the machine are located the two brackets 20, in which are housed bearings for a long horizontal shaft 22. One end of this shaft is extended toward the center of the machine and to this end of the shaft is attached a sprocket 24 over which is trained the chain 25 which passes around a sprocket 26 located on the end of a shaft 27 mounted in bearing brackets 28 on the platform 14. A chain 38, trained over sprocket 39 on the end of shaft 27 and over sprocket 40 on the armature of motor 18, drives the shaft 22 through the connections recited to rotate the traversing shaft in the direction of the arrow in Fig. 2. On the shaft 27 is fixed the pulley 30 which, through the belt 31 and pulley 32, drives a variable speed transmission of any preferred commercial type located on the platform 14 and given the reference numeral 33. This output speed from the transmission unit is controlled by the rotation of shaft 34 connected by a universal joint to the shaft 35 of hand wheel 36. The driven shaft of the variable speed transmission drives pulley 37, which, through belt 41, drives the pulley 42 on a countershaft 44 located in bearings 45 mounted on the rear of platform 14. On the end of shaft 44 is a sprocket 46 which, through chain 47 and sprocket 48, drives the shaft 50 of the traversing cam, as will be described.

Returning now to the shaft 22, which may be designated as the traversing shaft: Seated in the shaft 22, near the ends thereof, are two keys 52 and 53, located on opposite sides of the shaft for balancing purposes. The key 52, which is remote from the sprocket, is surrounded by a collar 54 which is keyed to the shaft through the key 52 and slides thereon. Force fitted about the collar is a sleeve 56, the outer surface of which is formed with a groove 57 in which the traversing lever engages. The inner face of the sleeve is formed with an annular ledge 59 which forms a seat for one end of the central traversing drum or cylinder 60.

The other key 53 is surrounded by a sliding collar 62 similar to the collar 54, and over this collar is force fitted a second sleeve 63 provided with the seat 64 to receive the other end of drum 60.

The drum 60 is welded to the sleeves 56 and 63 so that it rotates with the shaft 22 and moves to and fro thereon as it is reciprocated by the traversing cam and lever. An oil hole 68 is provided in the drum through which oil is introduced to the interior of the drum. Along the surface of the drum are located the roughened areas 66, equal to the number of cradles on that side of the machine. The roughened areas are sufficient in extent so that during the entire reciprocating movement of the drum the several balls will be in contact with their respective roughened areas.

On the rear of the top plate 10, opposite the grooved sleeve 56, is located a housing 70 which forms bearings for the shaft 50 and which also houses the traversing cam 72. The surface of the cam is cut with a cam groove 74, the configuration of which is carefully calculated and laid out so that the balls will turn in their cradles so as to present different positions with respect to the on-coming thread, which, in combination with the rolling of the balls in the cradles, will lay the cord wrapping evenly and uniformly over the surface of the ball. The cam groove, as it has been developed, is shown in detail in Fig. 7 and it will be found that in the machine as de-

signed this form of cam groove will turn the ball on one axis while it is being rolled about the other axis, in such manner that the cord layers are regularly and evenly applied, with no high or low spots on the ball.

The housing is cut away at the top so as to receive one end of a rocking lever 75 having a roller 76 which tracks in the groove 74, a cover plate 78 on the housing keeping the roller in the groove.

The central part or fulcrum of the lever 75 rests in a channel found in the top of a pivot block 80. A bolt 81 passing through a slot 82 in the lever holds the lever in the pivot block. The block 80 has a downwardly extending pin 84 which rocks in a bearing sleeve 85 fitted in the upper arm of a bracket 86. The lower end of the pin 84 is threaded to receive the lock nuts 88 bearing against the interposed washer 89. The base of the bracket 86 rests on the top of the bed plate 10, to which it is held by bolts 91 passing through the base of the bracket and through slots 93 in the bed plate to be threaded into a clamping plate 94 bearing against the under side of the bed plate. The adjustments provided at the fulcrum point of the lever 75 and at the base of the bracket permit the fulcrum point to be shifted so as to vary the effective throw of the lever, which in turn varies the extent of the end-wise movement of the traversing drum. This adjustment is necessary to enable the machine to operate upon balls of varying diameters. The two sides of the machine will have somewhat different locations for the pivot point 82 as the second winding operation will be performed on a ball of initially greater diameter than the initial diameter of the ball in the first winding operation. Also, this adjustment makes it possible to wind balls of a wide range of sizes.

To the outer end of lever 75 is welded a fork 96, the arms of which embrace the end of the traversing drum 60 at the sleeve 56. Rollers 98, projecting inwardly from the fork, engage the groove 57 to shift the drum back and forth along the shaft 22 during its rotation.

In the machine which is illustrated, six balls will be wound at the same time, three on one side of the machine and three on the other side, but the machine may be adapted for winding any number of balls simultaneously. Six ball winding operations are sufficient to keep a single operator busy at one machine.

Each ball is held in a cradle 100, in the side of which toward the drum is formed a socket 101 to receive a portion of the ball. The ball rest is completed by a replaceable plate or lip 102 held by bolts 103 on the main body of the cradle. The configuration of the complete socket is such that the ball will rotate therein and will stay in the socket during the winding operation. Each cradle 100 is provided with a downwardly extending arm 104 which is pivoted on a pin 105 extending across the arms of a fork 108, which span the arm 104. The fork 108 is formed on the upper end of the shorter vertical arm of an L-shaped lever 110, the horizontal arm of which extends to the rear of the machine. As shown in Fig. 1, the inner lever 110a of each set is offset so as to avoid the drive mechanism for the shaft 54. Each lever 110 (or 110a) is pivoted at the angle of the lever on a pin 112 extending across the forked end of an angular bracket 114, the outline of which is shown in Fig. 5. The bracket is secured to the face of the beam 12 by

bolts 115, the beam being notched at 113 to receive the lever 110.

When the cradle is in winding position, with the ball B in contact with the traversing drum 60, the plane of the cradle is at right angles to the vertical arm of the lever 110, but when the lever is operated to remove the cradle to its open position the cradle will pivot about the center 105 to the position shown in dotted lines in Fig. 2, so that the finished ball may be removed and a new core put in place. The position of the cradle is controlled by a short link 120, the outer end of which is pivoted at 121 to the lower end of arm 104 and the inner end to a plate 122 fixed to the bed plate.

The cord C, which is shown to the right of Fig. 3 as a dual cord coming from two spools D through a guiding eye 124 attached to a convenient part of the machine, here shown as the lower side of bracket 111, passes through a tensioning mechanism 125 and through a hole 126 in the base of the cradle to the ball. The tensioning mechanism may be of any desired type, that shown in Fig. 6 of the drawings being composed of two disks 128 which are yieldingly pressed together against a shoulder 129 on a pin 130 set in the end of the arm 110 just below the cradle. A coil spring 131 confined by the nut 132 on the end of the pin places the requisite tension on the cord. A duplicate tensioning mechanism 134 may be provided if found desirable.

The inner end of each lever arm 110 carries an adjustable weight 135 which is movable along the arm and is held in adjusted position by the spring operated pin 136 set in the lower part of the weight, with its pointed end engaging one of the several notches 137 along the arm.

The extreme inner end of the lever 110 is received in the vertical slot 141 of a block or stirrup 140, which is threaded onto the upper end of a piston rod 142 connected to the piston of a double-acting pressure cylinder 144, which is attached by brackets 145 to a plate 146 depending from the rear of the bed plate 10. A solenoid operated valve 148 located on the platform 14 beneath each cylinder controls the flow of air under pressure to the sides of the piston. The upper limit to which the end of the lever arms can move in the slot 141 is governed by a long set screw 150 threaded into the top of the block 140 and extending through a hole 151 in the bed plate, the upper end of the set screw having an operating knob 152.

Each individual solenoid valve 148 is controlled and operated to admit air to the cylinder 144 to raise the block 140 and thus rock the lever 110 and shift the cradle to its outward position by any standard form of timing mechanism for each cradle shown in Fig. 2 at 154. Details of the timer are not shown as these instrumentalities are well known, it being sufficient to say that at the end of a period set so as to complete the winding operation on that ball, the timer will actuate the solenoid valve and rock the lever 110, which shifts the ball out of contact with the drum 60.

When the operator has removed the wound ball from each cradle, he cuts the cord, and then after applying a few wraps of the cord by hand about a new ball or core he places that ball in the cradle and presses the button 156, which is connected to that timer circuit. Pressing the switch 156 resets the timer and, at the same time, reverses the cylinder 144 and lowers the block

140. The weight 135 will rock the lever 110, which brings the ball into contact with the drum 60, restores the cradle to its upright position, and the winding operation starts immediately.

5 The slot 144 permits the lever to move independently of the block 140 as the winding on the ball builds up.

It is believed that the operation of the machine will be clear from the foregoing and a brief resume will be sufficient. When the machine is idle, all of the cradles are in their outermost position, ready to receive a ball or ball core. The several set screws 150 are adjusted for the initial diameters of the balls which are to be placed in the cradles connected therewith, and the weight 135 is located to set the required pressure of the ball against the drum. The operator starts the motor by the switch 19 and the drum 60 starts to revolve idly and to be moved back and forth by the traversing cam. The operator makes the preliminary wrap of cord about a ball and places it in one of the cradles. He then presses the switch button 156 for that cradle and the valve 148 lowers the block 140, which, with the weight 135, rocks the lever 110 and moves the cradle to winding position with the ball held by the weight against the roughened area 66 on the drum. At the same time, the timer is reset and starts its operation, and when the timer has completed its predetermined cycle, the cylinder 144 is reversed by the solenoid valve 148 and the lever 110 is raised, removing the ball from contact with the drum, which stops the winding operation. During the winding operation, the ball is rotated in the cradle by the rotation of the drum and at the same time the plane of rotation is being constantly shifted by the cam controlled reciprocation of the drum. The combined movements create an even and uniform winding of the ball, the depth of each winding being controlled by the predetermined time cycle.

As the first ball starts its winding, the operator places another ball in its cradle and starts that operation, and so on down the line of cradles. As the last ball is placed in position, the first one is ready to come off the machine, but even if the operator is not ready to take a ball out of the machine at the time that cradle is moved outwardly, no harm is done as the wound ball is no longer rotated.

It will be seen that an extremely efficient machine has been devised for the purpose and that the operation of the machine creates accurate and uniform winding. The few adjustments that are required are easily mastered and the machine is capable of long operation without attention on the part of the operator, whose sole duties are to place and remove the balls and press buttons. Where the term "cord" is used in the specification and the claims it is understood that any type of cord or filament is intended.

What is claimed is:

1. A ball winding machine comprising an elongated drum, means to rotate the drum, means to reciprocate the drum on its axis during rotation, a plurality of arms, one of which is located adjacent each drum, an open cradle on each arm in which a ball may freely rotate, yielding means acting on each arm to hold a ball in its cradle in contact with the drum, individual time controlled means acting on each arm to shift the arm and separate the ball carried thereby out of contact with the drum, and means to feed cord to the balls in the several cradles.

2. A ball winding machine comprising an elongated

gated drum, means to rotate the drum, means to reciprocate the drum on its axis during rotation, a plurality of arms located adjacent each drum, an open cradle on each arm in which a ball may freely rotate, yielding means acting on each arm to hold a ball in its cradle in contact with the drum, means to shift each arm to bring the ball thereon into contact with the drum, individual time controlled means acting on each arm to shift the arm and separate the ball carried thereby out of contact with the drum, and means to feed cord to the balls in the several cradles.

3. A ball winding machine comprising an elongated ball winding drum, means to rotate the drum and at the same time to reciprocate it axially, a pivoted lever in the machine having one end thereof adjacent the drum, a cradle on that end of the lever having a socket to receive a ball, yielding means acting on the lever to hold the ball in contact with the drum, and means to rock the lever about its pivot to remove the ball from the drum at the end of the winding operation, said means comprising a block having a slot therein of sufficient extent to allow the lever to rock independently of the block as the ball increases in diameter, power means to move the block sufficiently to rock the lever and move the ball out of contact with the drum and time controlled means to actuate the power means.

4. A ball winding machine comprising an elongated ball winding drum, means to rotate the drum and at the same time to reciprocate it axially, a pivoted lever in the machine having one end thereof adjacent the drum, a cradle on that end of the lever having a socket to receive a ball, a pivotal mounting for the cradle in the end of the lever, a link connecting one end of the cradle to the machine, yielding means acting on the lever to hold the ball in contact with the drum, and means to rock the lever about its pivot to remove the ball from the drum at the end of the winding operation, said means comprising a block having a slot therein of sufficient extent to allow the lever to rock independently of the block as the ball increases in diameter, power means to move the block sufficiently to rock the lever and move the ball out of contact with the drum and time controlled means to actuate the power means.

5. A ball winding machine comprising an elongated ball winding drum, means to rotate the drum and at the same time to reciprocate it axially, a pivoted lever in the machine having one end thereof adjacent the drum, a cradle on that end of the lever having a socket to receive a ball, yielding means acting on the lever to hold the ball in contact with the drum, and means to rock the lever about its pivot to remove the ball from the drum at the end of the winding operation, said means comprising a block having a slot therein of sufficient extent to allow the lever to rock independently of the block as the ball increases in diameter, means to vary the effective length of the slot with reference to the diameter of the unwound ball core, power means to move the block sufficiently to rock the lever and move the ball out of contact with the drum and time controlled means to actuate the power means.

6. A ball winding machine comprising an elongated ball winding drum, means to rotate the drum and at the same time to reciprocate it axially, a pivoted lever in the machine having one

end thereof adjacent the drum, a cradle on that end of the lever having a socket to receive a ball, a pivotal mounting for the cradle in the end of the lever, a link connecting one end of the cradle to the machine, yielding means acting on the lever to hold the ball in contact with the drum, and means to rock the lever about its pivot to remove the ball from the drum at the end of the winding operation, said means comprising a block having a slot therein of sufficient extent to allow the lever to rock independently of the block as the ball increases in diameter, means to vary the effective length of the slot with reference to the diameter of the unwound ball core, power means to move the block sufficiently to rock the lever and move the ball out of contact with the drum and time controlled means to actuate the power means.

7. A machine in accordance with claim 3 in which the said power means is a double-acting hydraulic cylinder.

8. A ball winding machine comprising an elongated winding drum, means to rotate the drum and at the same time to reciprocate it axially, a movable arm having one end thereof adjacent the drum, a hollow cradle on that end of the arm to receive a ball core, yielding means to move the arm in one direction to hold the ball against the surface of the drum, means to supply cord to the ball core, power means to move the arm in the other direction to withdraw the ball from the drum at the end of the winding operation, a lost motion connection between the power means and the arm sufficient to allow the arm to move independently of the power means until the completion of the winding operation, and time controlled means to actuate the power means to move the arm in the direction to withdraw the ball from the drum.

9. A ball winding machine comprising an elongated winding drum, means to rotate the drum and at the same time to reciprocate it axially, a movable arm having one end thereof adjacent the drum, a hollow cradle on that end of the arm to receive a ball core, yielding means to move the arm in one direction to hold the ball against the surface of the drum, means to supply cord to the ball core, power means to move the arm in the other direction to withdraw the ball from the drum at the end of the winding operation, a lost motion connection between the power means and the arm sufficient to allow the arm to move independently of the power means until the completion of the winding operation, time controlled means to actuate the power means to move the arm in the direction to withdraw the ball from the drum, and adjustable means to limit the amount of lost motion to set the machine for the bare core.
